UNITED STATES PATENT OFFICE.

FRANK A. E. MARSH, OF LYNN, MASSACHUSETTS, ASSIGNOR TO UNITED SHOE MACHINERY CORPORATION, OF PATERSON, NEW JERSEY, A CORPORATION OF NEW JERSEY.

FINISHING TOOL.

Application filed February 27, 1926. Serial No. 91,153.

This invention relates to finishing tools for use in the manufacture of boots and shoes and more particularly to rotary burnishing tools of the type embodying sectional, work-rubbing members.

Rotary finishing tools of the Xpedite type have a plurality of sectional, work-rubbing members each disposed diagonally and mounted upon one end of a flat spring. A flange at one end of a carrier sleeve overhangs the free ends of the supporting springs and limits the outward movement of said springs and the work-rubbing sections supported thereby under the influence of centrifugal force. The other ends of these springs are rigidly secured to the other end of the carrier sleeve, which is mounted directly upon a rotary shaft, and melted wax is supplied to the periphery of the tool at the rear as the work is applied to another point of the periphery at the front. The wax which has been applied by such a tool, usually to the leather heel of a boot or shoe, is pounded into the leather and almost immediately hardens when the shoe is removed from the tool. In order to secure the best results, work which has been waxed by application to such a tool is usually treated further by application to a rotary pad, comprising usually a cloth covered, rather stiff brush, and is given a final polish by means of a softer, uncovered brush. Heretofore, the smoothness of the application of wax by the finishing tool to the work has depended very largely upon the skill of the operator and a poor operator will waste wax by applying an excessive amount of wax so as to get an even distribution across the width of the heel and will run the tool excessively hot so as to make this large quantity of wax flow on smoothly. In view of this waste of wax and since smooth application of the wax materially reduces the period of application of the work to the polishing pad, it is an object of the present invention to provide an improved finishing tool, in the use of which just the requisite amount of wax will be applied smoothly and evenly even when handled by an unskilled operator.

To this end, in accordance with features of the invention, the illustrated finishing tool is provided with means for adjustably determining the initial tension of resilient supporting means for the work-rubbing sec-

tions and for limiting the in and out movement of the work-rubbing members and causing said members to approach one another more closely adjacent to their free ends. Such a finishing tool is economical in its use of wax and applies the wax more evenly and smoothly and with a minimum of noise.

Preferably too, and as is illustrated, the tool is constructed and arranged with a plurality of spacing rings interposed between the flange of the carrier sleeve above referred to and the free ends of the supporting springs. This gives the springs an initial tension which is adjustably determined by varying the number of spacing rings and provides for adjustably determining the approach of the outer ends of the work-rubbing sections that they may be caused to "toe in" to an extent determined by the circumstances of the particular work or the desires of the operator.

Moreover, the sectional, work-rubbing members of such tools have commonly been rounded upon their outer surfaces in order to lessen the liability of tool marks upon the work, and while such an arrangement is highly satisfactory, still better results may be obtained by bringing the actual work-contacting surfaces as near together as may conveniently be done within the limits of mechanical expediency and practical construction. To this end and in accordance with still another feature of the invention, the corners of each of the illustrated sectional, work-rubbing members are chamfered along their edges next to the adjacent members and the remaining portion of the work-contacting surface remains as an arc of the peripheral circle described by the rotating tool.

Still another object of the invention is to provide a finishing tool by the use of which the burnishing of leather bases of heels of boots and shoes to which rubber heel sections have been applied will be facilitated.

Accordingly, another feature of the invention consists in a novel sectional, burnishing tool in which the periphery is made up of a work-contacting surface and a relieved surface adjacent thereto merging into one another along a gradual curve. With such a construction the work-contacting surface applies wax to the leather heel base while the relieved section overlies the rubber heel section and avoids applying wax to

100

105

110

said section. Inasmuch as it is not found desirable to attempt to provide a polished wax finish on the rubber heel section, the prevention of the application of wax thereto during the finishing of the leather heel section means a saving of subsequent expense in the cleaning of the periphery of the rubber heel section as well as avoiding a material waste of wax. Moreover, in machines of this type melted wax is supplied to the periphery of the work-contacting part of the tool in a narrow stripe and is spread over the surface of the tool by means of a reciprocating brush. With the arrangement above described, any wax which is accidentally carried over into the relieved portion of the tool may readily be pushed back on to the work-contacting portion of the tool by the reciprocating brush because of the gradual merger of said surfaces.

These and other features of the invention will now be set forth in detail with reference to the accompanying drawings, in which

25 Fig. 1 is a perspective view of the end of a machine to which my novel tool has been applied;

30 Fig. 2 is a longitudinal section through the tool and the supporting shaft, showing one position assumed by the work as it is applied to the tool;

35 Fig. 3 is a transverse section upon the line line III—III of Fig. 2 through the ends of the section-supporting springs and cutting the spacing rings by means of which said springs are tensioned; and

40 Fig. 4 is a perspective view of a single section of the tool with its spring, detached from the carrier.

45 The illustrated finishing tool comprises a carrier member 10 in the form of a sleeve having an enlarged end 12 to which flat springs 14 carrying sectional, work-rubbing members 16 are firmly secured by means of stud screws 18. The outer end of the sleeve 10 is formed to provide an overhanging flange 20, which co-operates with the ends of the springs 14 to limit the outward movement of the work-rubbing members 16 under the action of centrifugal force. The tool is mounted at the free end of a rotary shaft 22 and is held in place thereon by means of a tapered bolt 24 having a wrench socket 26. Wax is supplied to the tool from a receptacle 28 by means of a driven wheel 30 arranged to lift the wax from the receptacle and apply it in a stripe to the periphery of the wheel over which it is spread by means of a reciprocable brush 32 power operated to traverse the whole outer face of the tool. The general contour of the tool illustrated is that of the frustum of a cone and the machine is preferably provided with a casing having an overhanging flange 34 which surrounds the larger end of the

cone so that any wax thrown off will be retained within said flange and prevented from flying on the operator. A tread rest 36 adjustably mounted upon a slide 38 is positioned, as indicated in Fig. 2, to provide a support for the tread surface of the heel of the shoe to be burnished. Since the slide 38 may be moved to a point such that wax may be thrown off from the tool back of the tread rest 36, a depending curtain 40 which is illustrated as secured to the slide 38 is provided for the protection of the operator. A hand-operated clamp 42 is provided for holding the slide 38 in adjusted position upon the machine.

50 The illustrated tool is particularly adapted for use upon the leather bases 44 of heels to which a rubber top section 46 has been applied. Commonly the edge of the rear end of the sole 48 is treated at the same time as a continuation of the surface of the heel base 44. It is found in practice that the rubber top sections cannot well be burnished and that the wax used for burnishing the leather portion of the heel does not stick to the rubber. As a result, if wax is accidentally applied to the rubber top section, it is wasted and moreover must be removed by application to a rotary pad wheel or by cleaning in the packing room. Accordingly, in the construction illustrated, the sections 16 making up the periphery of the iron are each provided with a work-contacting surface 50 of limited extent and with a relieved surface 52 adjacent to said work-contacting surface and connected thereto by a gradual curve 54. If, then, the tread rest 36 is properly adjusted so that the shoe assumes the position indicated in Fig. 2, wax will only be applied to the parts 44 and 48, which it is desired to burnish, and no wax will be applied to the rubber top section 46 because the latter is positioned opposite to the relieved portion 52 of the iron. It will be understood that the wax-feeding wheel 30 is so positioned that it applies a stripe of wax to the work-contacting surfaces 50 of the various sections and that the reciprocating brush 32 is effective to spread this wax over said surfaces during rotation of the tool. If, as a result of this spreading action, wax is carried over on to the relieved surfaces 52 of the tool the action of the brush 32 is equally effective to carry it back on to the work-contacting surfaces 50 because of the gradual curve 54 connecting the two portions. Although the illustrated iron is designed for use upon the heels of men's shoes of a particular height, it will be obvious that other irons may be designed for use upon other heights of heels or upon the heels of women's shoes without departing from the invention.

55 Although tools of the Xpedite type, such as that herein illustrated, are remarkably efficient in applying wax to the peripheries

of heels for the purpose of providing a durable and attractive finish thereon, it has been found that there is considerable variation in the results obtained by different operators according to the skill which they possess and the care which they use in the operation. With the poorer operators wax may be applied in such quantities and in so irregular a fashion that, although it provides just as durable and attractive a finish in the final product, it nevertheless is not only likely to be wasteful of wax but requires a greater amount of work to be performed subsequent to the operation performed by this particular tool, as by means of a pad or brush, in smoothing up the wax surface and giving it the high lustre which is desired. Accordingly, the illustrated organization is designed to provide greatly improved burlining even when an unskilled operator is employed. To this end means are provided for limiting the in and out movement of the free ends of the springs 14 upon which the sections 16 are mounted, which limitation, in the illustrated embodiment, is effected by the insertion of a plurality of flat rings 60 between the overhanging flange 20 of the carrier sleeve and the outer ends of the supporting springs. The desired effect may be obtained by using a greater or less number of rings 60, and in any event it will cause the outer ends of the various sections 16 to "toe in" or approach each other more closely and will at the same time apply an initial tension to the supporting springs 14. The tensioning of the springs 14 gives them an additional reactive force against pressure applied to the work-rubbing sections 16 and tends to stiffen them against longitudinal twisting strains so as to make the positions of the various sections more rigid. In the illustrated construction, limitation of the in and out movement is secured by the use of rings as described and in addition the various sections 16 are secured to the supporting springs 14 by means of rivets 62 which pass through reinforcing strips 64, and it will be observed from Fig. 2 that the heads of the inner set of rivets are brought close to a projecting rib 66 upon the carrier sleeve. At the same time the inner sides of the outer ends of the reinforcing strip 64 are close to another rib 68 upon the sleeve so that inward movement of the various work-rubbing sections is either limited or eliminated, as may be desired. With this iron even the least skilled operator is able to apply wax so smoothly that a minimum of additional work is required upon the polishing pad or brush.

Because of the practical limits of good mechanical design there is a substantial space between the various parts of the various contacting sections. In order that this

may be minimized as much as possible and the effect of causing the sections to "toe in" may be even more emphasized, the corners of the meeting edges of the work-contacting portions 50 of the various sections have been chamfered or beveled to a limited extent as shown, much exaggerated, at 70 and 72 along each side of each section. The possibility of tool marks is minimized by this construction and the smooth action of the tool is improved because of the lessened space between succeeding members. The intermediate or work-contacting surfaces 50 preferably are formed so that a transverse section through the tool cutting these surfaces would intersect the surfaces along the arcs of a circle.

Having described the invention, what I claim as new and desire to secure by Letters Patent of the United States is:

1. A finishing tool comprising a carrier member, sectional work-rubbing members, means for resiliently supporting said members at a point remote from the point of application of work to the tool, and adjustable means for limiting the in and out movement of said work-rubbing members arranged to apply an initial tension to the resilient supporting means prior to the application of work to the tool.

2. A finishing tool comprising a carrier member, sectional work-rubbing members, flat springs having ends attached to said carrier member and supporting the sectional members at their other ends, fixed means upon said carrier members for limiting the in and out movement of the work-rubbing members, and additional means cooperating with said fixed means adjustably to apply an initial tension to said springs prior to the application of work to the tool.

3. A finishing tool comprising a carrier member, sectional work-rubbing members, springs attached to said carrier member at one end and arranged to support the sectional members at a point remote from the point of attachment of the springs, said springs being normally disposed in positions parallel to the axis of the tool, and adjustable means constructed and arranged to bend in said springs to place them under an initial tension prior to the application of work to the tool.

4. A finishing tool comprising a carrier member, sectional work-rubbing members, normally untensioned resilient members supporting said work-rubbing members, and means for adjusting said resilient supporting members radially constructed and arranged for determining the circumferential spacing of one end of the various work-rubbing members and to apply an initial tension to the resilient members.

5. A finishing tool comprising a carrier member, sectional work-rubbing members,

flat springs attached to said carrier member at one end and supporting the sectional members at their other ends, a flange upon said carrier member overlying the free ends of said springs, and a plurality of rings interposed between said flange and the free ends of said springs constructed and arranged to apply an initial tension to the supporting springs prior to the application of work to the tool.

6. A finishing tool comprising a carrier member, sectional work-rubbing members resiliently supported upon said carrier member at a point remote from the point of application of the work, and means adjacent to the point of application of the work constructed and arranged to restrain the outward movement of said members and to cause said members to approach one another more closely at their ends remote from the point of attachment to the carrier member than at their other ends.

7. A finishing tool comprising a carrier member, sectional work-rubbing members, and means for adjusting said members radially, thereby to determine the circumferential spacing of one end of the various work-rubbing members.

8. A finishing tool comprising a carrier member, sectional work-rubbing members, resilient members supporting said work-rubbing members, and means for adjusting said resilient supporting members radially, thereby to determine the circumferential spacing of one end of the various work-rubbing members.

9. A finishing tool comprising a carrier member, sectional work-rubbing members, resilient members supporting said work-rubbing members attached to said carrier member at a point remote from the point of ap-

plication of the work to the tool, and means for adjusting said resilient supporting members radially, thereby to determine the circumferential spacing of one end of the various work-rubbing members.

10. A finishing tool comprising a rotatable carrier member, sectional work-rubbing members supported upon said carrier member having work-contacting surfaces of limited extent and relieved surfaces adjacent to said work-contacting surfaces, said relieved surfaces merging into the work-contacting surfaces along gradual curves to facilitate the return of wax from the relieved surfaces to the work-rubbing surfaces.

11. A finishing tool for the application of melted wax to the leather base section of a shoe to which a rubber top-lift section has been applied comprising sectional work-rubbing members having a generally conical contour, a wax guard arranged to overhang the larger end of said conical tool thereby to prevent scattering of wax from said tool by centrifugal force, the surface of said tool being divided into a restricted finishing area suitable for the application of wax to the heel base section of said shoe and a relieved area arranged to avoid the application of wax to the rubber heel toplift section, and means for spreading wax over the surface of said tool, said tool being constructed and arranged so that the relieved section of its surface merges gradually into the work-rubbing section of the surface whereby said spreading means is enabled to return to the work-contacting surface of the tool wax carried over into the relieved section of the tool.

In testimony whereof I have signed my name to this specification.

FRANK A. E. MARSH.
